UNITED STATES PATENT OFFICE

RICHARD VON REPPERT, OF HARTFORD, CONNECTICUT, ASSIGNOR TO UNDERWOOD
ELLIOTT FISHER COMPANY, OF NEW YORK, N. Y., A CORPORATION OF DELAWARE

TYPEWRITING MACHINE

Application filed September 11, 1928. Serial No. 305,175.

This invention relates to a power-driven type-action for typewriting and computing machines which is initiated by the depression of a key.

5 In this invention the power-driven type-action is controlled mechanically, wherein the depression of a key releases a latch which is carried by a pressure lever. The latter, through spring tension, forces a wedge-like 10 interponent into engagement with a power-cylinder, which, through friction, actuates the type-bar to strike against the platen, whereby the pressure on the key need not be directly transmitted to cause the frictional 15 engagement. As no direct key-pressure is needed for operating the type-bars, a very light pressure on the keys is sufficient. This relieves the operator from strain, while at the same time a blow of the desired force 20 may be obtained to cause a proper imprint on a work-sheet.

A feature of this invention lies in the speed with which the keys may release associated members to actuate the type-bars.

25 Another feature is the use of means, whereby, when a key is depressed, an inadvertent second pressure on said key does not cause an error in typing or computing.

A feature of this invention lies in the use 30 of a constantly-driven cylinder or power device having numerous circumferential gripping grooves corresponding with a set of key-controlled wedge-shaped interponents, which are caused by the keys to drop into the 35 grooves, and which are hence set in motion by the cylinder, their motions being duly transmitted to the type-bars. Through said grooves and wedges a frictional coupling is obtained, which is well adapted to operate 40 typing and computing mechanisms. The desired friction is obtained by using a sharp angle in the grooves, and by applying pressure to the wedge-shaped interponents. According to the invention the engaging pres- 45 sure of the wedges is supplied by a spring-actuated member which is merely released by the keys and automatically reset by the power devices. By these means the power device supplies the force necessary to oper- 50 ate the typewriting devices and the keys have

merely a selecting function and therefore require a light and short stroke.

Other features and advantages will hereinafter appear.

In the accompanying drawings, 55

Figure 1 is a vertical section through a typewriting machine, and shows this invention applied thereto.

Figure 2 is a perspective view of this invention, with some parts broken away or 60 omitted.

Figure 3 is a partial vertical section through Figure 1, as viewed from the front.

Figure 4 is a detail view, showing the component parts of a power-cylinder. 65

Figure 5 is a detail view of the releasing and resetting members as positioned at the completion of the downward thrust of the pendant.

Figure 6 is a detail view, showing a type-bar 70 about to strike the platen, and the trip-lever about to be released to reset a pressure-lever.

Referring to the drawings, the keys 10 have key-levers 11, which are fulcrumed on a shaft 75 12, carried by the main frame 13 of a typewriter shown partly in outline. The key-levers are extended to form overhangs 14, connected by contractile springs 15, to a channel-piece 16, which is attached by screws 17 to 80 lugs 18, formed on said main frame. The key levers 11 have dependent arms 20, formed with stops 21, seats or latches 22, faces 23 and ears 24, and also have pins 25.

Pivottally attached to the ears 24 by studs 85 or screws 26, are stepping or latching levers 27 having stop-arms 28, latching seats 29 and faces 30. The dependent arms 20 and the stepping levers 27 are connected by contractile springs 31. The key-levers are separated by spacers 32, and are held against endwise movement by collars 33, which are attached by pins or set screws to the shaft 12.

Engageable by the dependent arms 20 and the stepping levers 27, are latches 34, which 95 are formed from, or are attached to, pressure-levers 35. The latter are pivotally mounted on a shaft 36, which is pinned in bossed on the main frame 13. The pressure-levers are separated on said shaft by spacers 37, and 100

are positioned as a unit through collars 38, which are held by set screws.

The free ends of the pressure-levers 35 are under tension of attached springs 39. The latter also are hooked to an angle-bar 40, which is attached to lugs on the main frame 13, by suitable screws. The pressure-levers 35 have short arms 42 that carry rollers 43, which are attached to said levers by studs 44.

10 A roller 43 can engage one edge of a device or pendant 45, which has an opposite edge formed into a wedge 46. The pendants are pivotally hung on studs or screws 47, carried by main levers 48. The latter, at their 15 forward ends, slide in, and are guided by, slots 19 cut into the channel-piece 16 to form a comb. At their other ends the main levers are fulcrumed at 49, and are held in normal raised position by springs 50, supported on 20 the main frame.

When depressed, the main levers 48 will actuate bell-cranks 51, to swing type-bars 52 up and away from a rest 53, and to strike a platen 54. The latter is carried by a shaft 55 journaled in a usual carriage 56, which rides on rails 57 that are supported on the main frame. A universal bar 58 is actuated by the type-bars 52, to operate a usual escapement-mechanism 59, which co-operates with common 30 carriage-feeding members 60.

Rearward actuation of the pendants 45 causes their wedges 46 to engage the beveled sides of disks 61, which are equidistantly separated by spacers 62. Said disks and spacers are assembled on the large diameter 63 of a turned-down driving shaft 64, which is provided with projecting right hand, or right and left hand, threads 65. Said large diameter has a key-channel 66, through which said 35 disks are kept from rotating. This may be done through a key formed on each disk to engage the key-channel, or by a usual key which is common to both the key-channel and to a slot cut through each disk.

40 The disks 61 and spacers 62 are held together and positioned longitudinally in cylindrical form by end washers 67 held by nuts 68. One end of said driving shaft 64 is journaled in a bushed boss formed on one side 45 of the main frame. Another support of said shaft 64 is a bushing 69, which is threaded into another boss on the main frame. The driving shaft 64 is held in its bearings by collars 70, which are provided with set screws. 50

55 The disks and spacers, when assembled, form annular grooves 71.

One end of the driving shaft is connected to a worm-gear 72, rotated by a worm 73, which is driven by a motor 74. The worm-drive is 60 enclosed in a gear-case 75, which, together with the motor, is bolted to the main frame 13. The speed of the driving shaft is governed by the ratio of the worm-drive, and also by the R. P. M. of the motor. The latter may 65 have a common variable-speed control.

When the motor has been started and the above-described machine is to be operated, the parts will normally lie as shown in Figure 1. When a key is depressed, the key-lever

70

swings its associated dependent arm 20, and slides the seat 22 from under the latch 34. The latter, through the pressure-lever 35 and the spring 39, will then be pulled down between the faces 23 and 30. This downward movement of said latch and lever swings the roller 43 to engage the pendant 45, and to press the wedge 46 into one of the grooves 71. The pendant, through its frictional engagement, will then be pulled down, and will actuate a main lever 48 to swing the type-bar up and against the platen. Before the type-bar strikes the platen, the parts will assume the relative positions shown in Figure 6.

75

As stated, a pendant is frictionally coupled and power actuated upon release of the respective key and to disconnect the pendant, a disconnecting and resetting device for the pressure-lever is provided.

80

The nether edge of the pressure-lever is developed into a cam arranged to be engaged by a roll 100 on an arm 99 of a rocker 93 and the rocker is held in normal position by a spring 95 secured to an arm 94 of said rocker and to the angle-bar 40. The foot of each pendant 45 engages a lever 78 journaled on the transverse shaft 80 which is mounted in bosses on the main frame and a spring 81 connects the lever 78 with the arm 92 on the rocker 93 formed with a hub 98 to rock upon a shaft 103 so that movement is transmitted from the pendant to the rocker through the spring 81. Normally, the parts are in the position shown in Figure 1, with the lever 78 against a stop 82, common to all the levers 78, and in this position the rocker 93 is locked against movement by the lever 85 engaging the lock surface 91 with the arm 92 of the rocker. The opposed arm 87 of the lever 85 has a cam surface adapted to be engaged by a pin 84 on the lever 78 and a spring 89 is connected to a pin 88 on the lever 78 and to a transverse bar 90 and holds the lever in normal position.

95

The downward movement of the pendant will tension the comparatively strong spring 81 connecting the lever 78 with the rocker 93, and when parts have assumed the position shown in Figure 6, the pin 84 on the lever 78 touches the cam surface on the lock lever 85 and is ready to rock the lever about its shaft 86 to thereby release the rocker 93.

100

Upon a limited additional movement of the pendant, the parts will assume the position shown in Figure 5 and in this position the pin 84 has actuated the lever 85 and has released the rocker 93, which, through the tension of the spring 81, has instantly moved to actuated position. This movement of the rocker 93 causes the roll 100 on the arm 99 thereof, to actuate the cam edge on the pressure-lever 35,

105

110

115

120

125

130

thereby raising the pressure-lever to a position wherein the latch 34 thereon can be re-engaged by the seat 29 of the stepping lever 27.

5 As the key is released, the seat 29 of said stepping lever 27 will slide out from under the latch 34 through the abutment of the pin 25 with the stop-arm 28 and the seat 22 of the key-lever will position itself under the latch 34, and shortly before the key re-assumes normal position, the stepping lever will be disengaged entirely from the latch 34 and the latch will drop onto the seat of the key-lever under the impulse of the spring 39 and the parts 10 will assume normal position.

15 In Figure 1 the face 30 abuts the side of the latch 34 because the seat 22 is lower than the seat 29. This permits the latch to drop when the seat 22 is withdrawn. As soon as a key 20 has been depressed and the latch 34 has started down, the engagement between the latch and the face 23 will prevent the key from rising to normal position. While so locked an inadvertent second pressure on the key would 25 not cause an error in typing, because the type-bar will be automatically actuated but once between the depression and release of a key. The depression of the latter is limited when the stops 21 abut the channel-piece 16. The 30 latter serves a four-fold purpose, namely, it acts as a stop for the keys, it functions as an anchorage for the springs 15, and also both guides and stops the main levers 48.

The spring 81 performs dual functions. 35 First, as shown in Figure 6, it is expanded to pull down the arm 92 when released by the latch-lever 85. After such release, the spring 81 contracts, and the parts assume the positions shown in Figure 5. During the restoration of the parts to the positions shown in 40 Figure 1, the spring 81 merely acts as a link. Such function of the spring 81 is possible through its having a greater tension than the correlative spring 95.

45 When the disks 61 and spacers 62 have been assembled and fixed on the shaft 64, the whole constitutes a power-cylinder having grooves 71. Should the latter become worn to the point of slippage, the disks can be replaced. 50 The grooves register with the pendants 45 carried by the main levers 48, which are equidistantly spaced in the slots 19. The rollers 43 are registered with said pendants, while the latches 34 on the associated pressure levers 55 will register with members 20 and 27, which are connected to the keys.

With the construction shown, wherein all the key-levers have a common fulcrum, there will be four series of said levers, each series 60 having a different length. If all the keys are depressed the same distance, the longer key-levers will not swing the dependent arms through as great an arc as will the shorter key-levers. If not swung far enough, the dependent arms would not release the latches. 65

The last-mentioned possibility is overcome by providing four series of dependent arms, each series having a different length of seats 22, the shortest seats functioning with the longest key-levers. Another provision is 70 four different lengths of stops 21, to maintain the same depressed key-travel for the different lengths of key-levers. In this case the longest levers have stops which project the furthest. Figure 1, therefore, shows the 75 stops 21 and seats 22 as proportioned for only the top row of keys, and this invention is not limited thereby.

The various releasing and restoring members have been shown as supported directly or 80 indirectly on the main frame of the typewriter. Without changing this invention, it would be possible to mount said members on a separate frame, which could then be adjustably attached to said main frame. 85

This invention as illustrated is applied to 90 a typewriter. It is equally applicable, and more advantageous, when used with a combined typewriting and computing machine. For such purposes connections are made from the main levers of the digit-keys to a totalizer or indexing mechanism. For these reasons it is not desired to limit this invention to the construction shown.

In providing for frictional engagement between the pendants and power-cylinder, the angle of the bevels is a feature of importance, and, in the design shown, the opposed walls of the friction groove are at an angle of about 95 twelve to fifteen degrees to each other. 100

The grooves are hardened to a somewhat softer degree than are the pendants or interponents and any slight slippage between the two will result in a uniform wear on the rotating power-cylinder rather than a grinding off of one area on the interponent. This insures continued smooth engagement surfaces, so that there is neither lag nor jerk when friction is applied. 105

It will be seen that when a key is depressed, a seat on an associated arm is swung out from under a latch and releases the same. The latch forms part of a pressure-lever, which is pulled down by a spring when released. The pressure-lever has a free arm at right angles thereto, carrying a roller, which is thereupon swung rearwardly. The roller engages the front edge of an interponent-member having a rear edge formed into a wedge. This interponent-member is pivotally suspended on a main lever connected to the type-bar and computing mechanism. 110 115 120

The interponent-member is swung rearwardly by the roller, and the wedge engages one of a series of V-shaped grooves in a power-driven and normally-rotating cylinder. The latter, when so engaged constitutes a clutch, which, through friction, rolls down the interponent-member to depress the main 125 130

lever, and thereby actuates the type-bar and computing mechanism.

Just before the type-bar strikes the platen, which it does through momentum, the downwardly-traveling interponent-member is released from the clutch. This release is accomplished through a swingable lever, which underlies and is spring-held against the interponent-member. As the latter approaches a predetermined releasing position, the lever approaches the limit of its downward swing. As said lever swings, it also swings a pin carried thereon. The pin traverses a cam on the lower end of an oscillatable latch-lever, which is swung thereby.

Through the aforesaid cam the upper end of the latch-lever 85 is swung free from beneath the arm 92 carried by the rocker 93. Said arm 92 is then pulled down and toward the lever by the connecting spring 81. This movement of the rocker raises the attached roll 100 which, in turn, raises the spring-pulled end of the pressure-lever. The latch on the latter is caught and held in raised position on the seat of a stepping lever pivoted on the arm associated with the key. The arm and the stepping lever are for this purpose connected by a spring. As the pressure-lever, which carries the latch, is raised, the attached roller is actuated out of engagement with the interponent-member. The wedge on the latter thereupon ceases to have frictional engagement with the groove in the cylinder, and the interponent-member is raised to normal position. This is done by the spring which restores the main lever, after its associated type-bar has struck the platen.

As the interponent-member rises, the abutting lever 78 begins to rise through spring tension 81. The pin carried by the lever then retraverses the cam on the latch-lever, which has its lower end pulled rearwardly by a spring. The spring that resets the lever also rotates the rocker. This movement swings the roll-arm down and away from the pressure-lever. The arm 92 on the rocker rides up the front of the latch-lever, until the upper end of the latter is snapped under said arm. While the above actuating or resetting members are functioning, the key is held in depressed position, either by the operator's finger or by engagement of the associated arm with the side of the latch. As the key is released it is spring-pulled so that its associated seat may first underlie the latch. As the upward key movement continues, the seat of the stepping lever is actuated by a stop on its supporting arm until its seat slides from under the latch. The released latch then drops slightly onto the seat of said associated arm, where it is held until the key is again depressed.

A very slight rearward movement of the wedge is necessary for engagement with the groove, so that the pressure-lever travels but

a short distance between latched and unlatched positions. As the interponent-member is released and loses its actuating power, it is necessary to reset the latch by other means. This is done through the accumulated tension in the spring connecting the rocker, which instantly resets the latch, and permits the interponent-member to rise.

Variations may be resorted to within the scope of the invention, and portions of the improvements may be used without others.

Having thus described my invention, I claim:

1. A typewriter having the combination of a universal continuously-rotating friction clutch-member, type-bars, individual friction clutch-members connected to the type-bars, normally inoperative pressure-arms effective when released to press the individual clutch-members into engagement with the universal clutch-member, to frictionally transmit typing movements to the type-bars, keys having means to selectively release said pressure-arms, means for restoring said pressure-arms, and means operable by the typing swing of the type-bars and effective to store up energy in the pressure-arm-restoring means, said restoring means being automatically released near the completion of the typing stroke for the purpose of discontinuing the individual clutch-member pressure independently of the actuated key.

2. In a typewriting machine, the combination of a universal continuously-rotating frictional driving member, a type-bar, type-bar-driving devices engageable individually with the rotating member, a member for causing said driving device to engage said rotating member frictionally, a spring tending to operate said engaging member, a latch for normally restraining said engaging member, a key, means to enable the key to release said engaging member to swing the driving device into a frictional engagement with the rotating member, and maintain a frictional pressure between the driving device and the rotating member until the type-bar is actuated, and individual connections driven by the individual type-bar-driving devices, and each effective to set up an individual restoring power to re-latch said engaging member, said restoring power being subsequently released by the final portion of the power stroke of the type-bar-driving device.

3. A typewriter having the combination of a universal continuously-rotating friction clutch-member, type-bars, individual clutch-members connected to the type-bars, spring-actuated pressure members to connect the individual clutch-members with the universal clutch-member, to thereby transmit typing movement to the type-bars, keys operative to release the selected pressure members to induce clutching engagement of the respective individual clutch-members with the universal

clutch-member, and spring-actuated resetting devices connected to the type-bars to be set at tension during the typing stroke thereof and released upon or near completion of the typing stroke to reset the pressure members and thereby release the individual clutch-members and the type-bars associated therewith for resetting movement.

4. A typewriter having the combination of a universal continuously-rotating friction clutch-member, type-bars, keys having arms, individual friction clutch-members connected to the type-bars, spring-actuated pressure members normally held out of engagement, with the individual clutch-members by the arms on the keys, and operative to connect the individual clutch-members with the universal clutch-member, to thereby transmit typing movement to the type-bars, the keys operative to release the selected pressure members for inducing clutching engagement, and springs connected to the type-bars to store up energy during the typing movement and release this energy upon or near completion of the typing stroke for the purpose of restoring the type-bars and individual clutch-members, when the latter are released from the universal clutch-member.

5. A typewriter having the combination of a universal continuously-rotating friction clutch-member, type-bars, keys having arms, individual friction clutch-members connected to the type-bars, and spring-actuated pressure members normally held in unforced engagement with the individual clutch-members by the arms on the keys, and operative when released to connect the rotating and individual clutch-members, the pressure members having latches, the arms having seats to engage the latches through spring pressure, and the seats swingable to release the latches upon depression of the keys, to thereby transmit typing movement to the type-bars through the spring tension of the pressure members, which causes frictional engagement between the individual and rotating clutch-members.

6. A typewriter having the combination of a universal continuously-rotating friction clutch-member, type-bars, keys having arms, individual friction clutch-members connected to the type-bars, and spring-actuated pressure members normally held in unforced engagement with the individual clutch-members by the arms on the keys, and operative when released by the keys to connect the rotating and individual clutch-members, the pressure members having latches, the arms having seats to engage the latches through spring pressure, the seats swingable to release the latches upon depression of the keys, the keys having levers of various lengths, and the seats being of different lengths, whereby the same downward travel of the keys will always release the latches

when the arms of the keys are swung through arcs of various degrees.

7. In a typewriting machine, the combination of a universal continuously-rotating friction clutch-member, type-bars, individual friction clutch-members, connected to the type-bars, keys having latching arms, spring-actuated pressure-members having latches engageable by the arms to normally hold the pressure-members out of engagement with the individual clutch-members, said pressure-members when released by the keys operative to connect both clutch-members, rockers having means for restoring the key-released pressure-members, levers normally effective to latch the rocking means and each lever having a cam, arms depressible by each individual clutch-member and each arm having a stud, and a rocker-actuating spring connected to and flexed by the depression of each arm, each stud engageable with the cam of a latching lever to vibrate said lever and unlatch a rocking means to its tensioned spring and restore the pressure-member to the control of its key.

8. In a typewriting machine, the combination of a universal continuously-rotating friction clutch-member, type-bars, individual friction clutch-members, connected to the type-bars, keys having latching arms, spring-actuated pressure-members having latches engageable by the arms to normally hold the pressure-members out of engagement with the individual clutch-members, said pressure-members when released by the keys operative to connect both clutch-members, rockers having means for restoring the key-released pressure-members, levers normally effective to latch the rocking means and each lever having a cam, arms depressible by each individual clutch-member and each arm having a stud, a rocker-actuating spring connected to and flexed by the depression of each arm, each stud engageable with the cam of a latching lever to vibrate said lever and unlatch a rocking means to its tensioned spring and restore the pressure-member to the control of its key, and a stop on the machine, the downward swing of each stud-arm being limited by the throw of its individual clutch-member and the return of each stud-arm by its spring being limited by said stop.

9. A typewriter having the combination of a universal continuously-rotating friction clutch-member, type-bars, individual friction clutch-members connected to the type-bars, keys having latch-arms, spring-actuated pressure-members having latches releasable by the latch-arms to permit the pressure-members to connect the two clutch-members when the keys are depressed and thereby actuate the individual clutch-members to type, a spring-pressed arm having a stud, a spring-actuated rocker for each pressure-

member and having arms, and a lever for latching each rocker and having a cam, the stud engaging the cam on the latch-lever to swing the latch-lever out of engagement with one rocker-arm to release the rocker to its spring, another rocker-arm being swung up by the released rocker against its pressure-member, to raise the latter against its actuating spring, to disengage the pressure-member from its individual clutch-member to lease the latter from frictional engagement with the rotating clutch-member, and thereby permit the individual clutch-member to be restored.

10 15 20 25 30 35 40 45 50 55 60 65 70 75 80 85 90 95 100 105 110 115 120 125

10. In a typewriting machine, the combination of a universal continuously-rotating friction clutch-member, type-bars, individual friction clutch-members, connected to the type-bars, keys having latching arms, spring-actuated pressure-members having latches engageable by the arms to normally hold the pressure-members out of engagement with the individual clutch-members, said pressure-members when released by the keys operative to connect both clutch-members, rockers having means for restoring the key-released pressure-members, levers normally effective to latch the rocking means and each lever having a cam, arms depressible by each individual clutch-member and each arm having a stud, a rocker-actuating spring connected to and flexed by the depression of each arm, each stud engageable with the cam of a latching lever to vibrate said lever and unlatch a rocking means to its tensioned spring and restore the pressure-member to the control of its key, and a stepping lever pivotally mounted on said arm of each key and having means to engage the latch of the restored pressure-member to hold said restored member until the actuated key is released.

11. In a typewriting machine, the combination of a universal continuously-rotating friction clutch-member, type-bars, individual friction clutch-members, connected to the type-bars, keys having latching arms, spring-actuated pressure-members having latches engageable by the arms to normally hold the pressure-members out of engagement with the individual clutch-members, said pressure-members when released by the keys operative to connect both clutch-members, rockers having means for restoring the key-released pressure-members, levers normally effective to latch the rocking means and each lever having a cam, arms depressible by each individual clutch-member and each arm having a stud, a rocker-actuating spring connected to and flexed by the depression of each arm, each stud engageable with the cam of a latching lever to vibrate said lever and unlatch a rocking means to its tensioned spring and restore the pressure member to the control of its key, a stepping lever pivotally mounted on

said arm of each key and having means to engage the latch of the restored pressure-member to hold said restored member until the actuated key is released, and a stop on the arm of each key, said stop on the arm of the actuated key effective to rock its stepping lever holding the restored pressure-member, to release said member by releasing its latch to be rearrested by the restored arm of the key.

12. A typewriter having the combination of a universal continuously-rotating friction clutch-member, type-bars, type-bar operating levers, individual clutch-members connected to said levers, spring-actuated pressure members operative to connect the rotating and individual clutch-members to depress the latter, keys having levers operative to release and engage said pressure members, a cross-bar, springs for the key-levers anchored to the cross-bar to restore depressed keys when released, stops on the key-levers to abut the cross-bar when the keys are depressed, and slots in the cross-bar to guide the type-bar levers, the bottoms of said slots also acting as stops to limit the downward travel of the type-bar levers.

13. A typewriter having the combination of a universal continuously-rotating friction clutch-member, type-bars, individual friction clutch-members connected to the type-bars, spring-actuated pressure members having latches, and keys having arms, the arms having seats to intermittently underlie the latches, the arms carrying pivotal stepping levers pulled toward the arms by springs, the arms swingable by the depression of the keys to release the downwardly-spring-actuated pressure members, the stepping levers acting to underlie the latches when the latter are raised, the latches never lying below the vertical engaging surfaces of said arms and stepping levers, whereby said pressure members can always be raised between said vertical engaging surfaces, and whereby, after the keys have been depressed, and should the operator's finger be removed they are held in depressed position through the abutment of their vertical engaging surfaces with the sides of said latches until the latter are automatically raised above the seats on said arms, to permit the keys to be restored through their springs.

14. In a machine of the class described, the combination of typing devices, levers for driving the typing devices, pendants on said levers, a power-driven roller with which said pendants are frictionally engageable, keys separated from the typing-device-driving levers, and a train of mechanism intermediate each key and each pendant operable when a key is depressed to shift said pendant into frictional engagement with the power-roller for a typing-device-driving reciprocation, each train of mechanism including a

pressure-lever, a spring to tension said pressure-lever, a latch-lever for holding said pressure-lever at a tensioned position, a connection between the latch-lever and a key, and 5 a disk rotatably mounted on the pressure-lever and engageable with the pendant.

15. In a machine of the class described, the combination with a constantly rotating roller, a typing device, a lever for driving said 10 typing device, a key disconnected from said type-driving lever, a normally disengaged pendant mounted on said type-driving lever and frictionally engageable with the rotating roller, to enable the roller to drive 15 the pendant and typing device by friction with the pendant, and a pendant-controlling lever having means engageable with said pendant to swing the pendant into engagement with the rotating roller to be reciprocated thereby and drive the typing device, 20 of mechanism to enable the key to operate the pendant-controlling lever and force the pendant into a frictional engagement with the roller by the depression of the key.

25. 16. In a machine of the class described, the combination with a constantly rotating roller, a typing device, a lever for driving said 30 typing device, a key disconnected from said type-driving lever, a normally disengaged pendant mounted on said type-driving lever and frictionally engageable with the rotating roller, to enable the roller to drive the pendant and typing device by friction with the pendant, and a pendant-controlling lever 35 having means engageable with said pendant to swing the pendant into engagement with the rotating roller to be reciprocated thereby and drive the typing device, of intermediate mechanism connected to the key, 40 and connectible with the pendant-controlling lever to set up a type-device driving pressure between the pendant and the rotating roller.
